WHEEL UNBALANCE DETECTING UNIT

Arthur F. Dean, Glenview, and Anton J. Panzica, Hinsdale, Ill., assignors to Stewart-Warner Corporation, Chicago, Ill., a corporation of Virginia

Filed Jan. 12, 1961, Ser. No. 63,508

Term of patent 14 years

(Cl. D52—6)

FIG. 2.

FIG. 1 is a perspective view taken from the front and to one side of a wheel unbalance detecting unit embodying our new design, and

FIG. 2 is a perspective view taken from the rear and to said one side of the wheel unbalance detecting unit shown in FIG. 1.

The undisclosed side of the wheel unbalance detecting unit is substantially the same in appearance as the side shown.

We claim:

The ornamental design for a wheel unbalance detecting unit, substantially as shown and described.
